UNITED STATES PATENT OFFICE.

JOSEPH HAY AMIES, OF PHILADELPHIA, PENNSYLVANIA.

PAVING COMPOSITION.

No Drawing. Application filed April 4, 1924, Serial No. 704,251. Renewed November 19, 1925.

The object of this improvement is to produce the herein specified composition, to be employed, particularly, in the formation of sub-foundations, for street and highway constructions. It may, however, be used for flooring, roofing, and the like.

It can be placed upon any standard road foundation.

In accomplishing the results desired, it should be particularly noted, that very great, if not perfect condensation, can be secured in soil, when treated as herein described. Owing to the character and disposition of soil, all air and gases may be ex-

15 pelled, completely, because, soils will sufficiently inter-amalgamate and associate. It has been found that the voids in soil may be reduced, under heavy compression, to less than five per cent, whilst in broken, 20 stone and sand bituminous compositions, it has been found to be practically impossible to reduce the voids to less than twenty-six per cent.

It should be particularly noted, that the fine grade, must be fully steadfast. If it expands and contracts, the highway will lift and sink, from time to time. This is caused by the assumption of water and the draining off, thereof. If in a given space, 30 of the highway base, one ton of water is held at a given time, and at another given time, just after a copious rain fall, it holds ten tons of water, the bottom base of the grade will swell, and lift the entire super- 35 structure, of the highway, until the water drains off, and then the bottom grade will retire to its normal situation, whilst the super-structure may only retire partly down to the bottom grade, leaving depression and 40 unevenness at the bottom of the sub-foundation of the highway, which will express themselves upon the wearing surface of the street or road. This is because water is practically incompressible and will occupy, 45 persistently, one cubic foot of space for about every sixty-two pounds of water. Water on this account causes the bottom grade soil to swell and expand powerfully and lift the road super-structure. Ordinary drainage will not provide against this 50 destructive agent.

It is to be observed that in the construction of a highway, great satisfaction and convenience would be enjoyed in a concrete sub-structure, devised to secure an im-

mediate "setting". In that case, traffic could proceed without inconvenience, as soon as the road construction should have been finished. This would also be the means of preventing considerable additional cost, as compared to a concrete sub-structure that must be allowed many days, and perhaps several weeks, to allow for "setting", as is the case in the instance of what is called "re-enforced concrete highways".

The herein described composition will immediately harden and serve at once as a sub-foundation for any type of wearing surface.

I will now describe, in particular, my present composition adapted to give the foregoing stated desired results. I take local soil and place it in a suitable standard mixing machine. The mixing machine should be adapted to work the said soil into a finely macerated condition. If the soil does not contain moisture enough, in its natural state, (which however is very rarely the case), I may add a small additional amount of water to effect this result. Soil will become fully macerated by the action of the mixer, owing to the presence of moisture secured from the falling dews and rains, in addition to that normally attracted by chemical affinities. Soils will not surrender to evaporation, all moistures possessed by them, and taken up by capillary attraction but will retain considerable amount of water, secured from the deep ground where it is held and secreted, and therefore, usually, the soil, in its natural condition, provides all the moisture required in making my herein described composition. Usually, water, employed in making standard concretes, when carried from considerable distances, costs from ten to fifteen per cent of the total expense of manufacturing the concretes; because the quantity of water used in manufacturing standard concretes is equal to the bulk of the Portland cement employed. When the foregoing results have been secured, I add to each three measures of the finely macerated soil within the mixer, about one measure of the calcined sulphate of calcium.

The object of the mixing at this point, is to get a very intimate, inter-associated and amalgamated concrete composition, and the contents of the mixer, by this time, should be in a semi-dry state, and ready to

accept very heavy compression resulting in the forming of a very solid unyielding, semi-collodial, sub-foundation, before the initial "settling" will have begun. The particular advantage derived from this process, is, that this composition will become immediately very tough and unyielding. Little time need be extended to it before applying thereto any type of wearing surface. It may be, at once, given over to general traffic.

Having described my invention what I

claim as new and of particular advantage is:

The herein described paving composition consisting of natural soil mixed in the proportion of about three measures of water dampened soil with about one measure of calcined sulphate of calcium, for the purposes as herein specified.

In testimony whereof I have hereunto signed my name.

JOSEPH HAY AMIES.
